UNITED STATES PATENT OFFICE.

KUROJI SATO, OF RENO, NEVADA.

SHOCK-ABSORBER.

1,100,494.

Specification of Letters Patent. Patented June 16, 1914.

Application filed November 5, 1913. Serial No. 799,308.

To all whom it may concern:

Be it known that I, KUROJI SATO, a subject of the Emperor of Japan, and resident of Reno, in the county of Washoe and State of Nevada, have invented a new and useful Improvement in Shock-Absorbers, of which the following is a specification.

My present invention relates to vehicle springs, and more particularly to a spring mounting equally adapted to the fore and rear ends of a frame to be supported and involving a spring arrangement for the purpose of neutralizing heavy strains and sudden jolts and jars, being therefore in the nature of a shock absorber.

The object of my invention is to provide an arrangement which will be highly effective in its action, and strong and durable in use and I have shown an arrangement to this end in the accompanying drawings in which,

Figure 1 is a side elevation illustrating the parts under normal pressure. Fig. 2 is a similar view showing the parts in the positions they will occupy under sudden unusual strain or an excessive load, and Fig. 3 is a transverse, vertical section taken on an enlarged scale, through certain of the parts, substantially on the line 3-3 of Fig. 2.

Referring now to these figures, A indicates the main frame, and B indicates either the forward or rear axle, as the case may be. A lower leaf spring C is secured, by means of a yoke or other connection b, at a point adjacent to its inner end, upon the axle B and is suitably connected at its outer elongated opposite end to the adjacent end of the main frame A.

In the present instance I have shown the spring arrangement as applied to the rear portion of a vehicle in which case the rear end of the leaf spring C will be connected, by a link c, to the rear downwardly and inwardly curved end d of a leaf spring D, the opposite end of which is secured by a yoke or other means upon the rear end of the frame. It is to be noted, however, that in applying a spring arrangement to the forward portion of the main frame A, the outer elongated portion of the lower leaf spring C is directly united with the usual downwardly curved forward portion of the frame.

Secured at a central point to the extremity of the inner short end of the leaf spring C is a second leaf spring E, it being noted

that both the leaf spring C and leaf spring E last mentioned are disposed longitudinally with respect to the main frame and that the inner end of the upper spring E is connected, by a link e, to the frame A, intermediate the ends of the latter.

As shown particularly in Fig. 3 the outer end of the second leaf spring E supports a transverse pin e', to the laterally projecting extremities of which are connected the upper ends of spring arms F depending upon opposite sides of the elongated portion of the first spring C. A yoke or band C' is secured about the elongated portion of the first or lower spring C at a point between its outer extremity and the axle B, the lower portion of this yoke or band C' having transversely projecting pins c' to which the lower curved or curled ends of depending spring arms F are secured as by means of transverse bolts, rivets or similar connections. In this manner the several spring parts including the upper and lower leaf springs E and their connecting arms F act through one another to take up and neutralize all sudden jolts and jars and to effectively support heavy loads.

I claim:

1. In a shock absorbing spring arrangement of the character described, the combination of a supporting axle, a main frame, a longitudinally extended leaf spring secured at a point adjacent its inner end upon the axle, and having connection at its outer elongated opposite end to the adjacent end of the frame, a second longitudinally extended leaf spring secured at its center to the inner short end of the first leaf spring, the inner end of the second leaf spring being secured to the main frame at an intermediate point of the latter, a pair of spring arms secured to the outer end of the second leaf spring and having curved lower portions depending upon opposite sides of the first leaf spring, and a yoke secured about the first leaf spring at a point between its outer end and the supporting axle, and provided with laterally projecting portions to which the lower curved portions of the depending spring arms are secured.

2. In a shock absorbing spring arrangement of the character described, the combination of a supporting axle, a main frame, a longitudinally extended leaf spring secured at a point adjacent one end and having connection at its opposite end with the

main frame, a second leaf spring centrally connected to the short end of the first leaf spring and having connection at one end with the main frame and spring arms depending from the opposite end of the second leaf spring and having connection with the first leaf spring at a point intermediate its elongated end.

3. In a shock absorbing spring arrangement of the character described, the combination of a supporting axle, a main frame, a longitudinally extended leaf spring secured at a point adjacent its inner end upon the axle and having connection at its outer elongated opposite end to the adjacent end of the main frame, a second longitudinally extended leaf spring secured at its center to the inner extremity of the first leaf spring, the inner end of said second leaf spring being secured to the main frame, and spring arms depending from the outer end of the second leaf spring and having lower curved portions connected to opposite sides of the first leaf spring at a point intermediate the elongated outer portion of the latter.

4. In a shock absorbing spring arrangement of the character described, the combination of a supporting axle, a main frame, a longitudinally extended leaf spring secured at an intermediate point upon the axle and

having connection at its outer end to the main frame, a second leaf spring intermediate connected to the inner end of the first leaf spring, the inner end of said second leaf spring being connected to the main frame, and spring arms depending from the outer end of the second spring and having curved lower ends connected to the first leaf spring at a point intermediate the outer end portion of the latter.

5. In a shock absorbing spring arrangement of the character described, the combination of a supporting axle, a main frame, a longitudinally extended leaf spring secured at an intermediate point to the supporting axle and having connection at one end with the main frame, a second leaf spring having an intermediate connection with the opposite end of the first leaf spring and having connection at one end with the main frame, and a flexible connection between the opposite end of the second leaf spring and the first leaf spring at a point between the supporting axle and the frame connected end of the first leaf spring, substantially as described.

KUROJI SATO.
